Thomas R. Harvey
ATTORNEY.

UNITED STATES PATENT OFFICE.

JOHN HENRY ROSEMEYER, OF ELMIRA, IDAHO.

CABLE-HOLDING DEVICE.

1,393,245.

Specification of Letters Patent. Patented Oct. 11, 1921.

Application filed November 27, 1920. Serial No. 426,800.

To all whom it may concern:

Be it known that I, JOHN H. ROSEMEYER, a citizen of the United States of America, residing at Elmira, in the county of Bonner 5 and State of Idaho, have invented certain new and useful Improvements in Cable-Holding Devices, of which the following is a specification.

My present invention relates generally to 10 cable holding devices by means of which a cable grip may be completed without knotting and by which the cable may be readily and quickly connected and disconnected, and more particularly to what is known as a 15 cable take-up, my object being the provision of a simple inexpensive device which will present an integral structure and will promote effective and efficient operation at all 20 times without danger of excessive wear or inefficiency due to rust or other action of the elements.

With these and certain other objects to be hereinafter made plain, my invention resides in the construction shown in the accompanying drawing, which forms a part of 25 this specification, and wherein,

Figure 1 is a top plan view illustrating the practical application of my invention,

Fig. 2 is a side view,

Fig. 3 is a longitudinal section, and,

Fig. 4 is a transverse section.

Referring now to these figures, my invention proposes a take-up including a ring shaped body 10 having a peripheral groove 11 adapted to receive the loop 12 of a cable 13, the body being open for the convenient reception of a hook 14 and the like of a pull line 15, as shown in Fig. 1.

The body 10 is preferably of oval form 40 and provided with an external substantially flat extension 16 at, and projecting beyond, one end, which extension is of materially less width than the width of the body 10 and has its inner or upper surface substantially in the 45 plane of the groove 11 so as to receive the cable 13 adjacent to the loop 12 in crossing relation above the free end 17 of the cable.

At the outer end of the extension 16 is a cable guide 18 disposed transversely thereof 50 and preferably integral therewith, the opposite ends 19 and 20 of which project beyond opposite sides or edges of the extension and respectively receive therebeneath the cable 13 and its free end 17. The projecting end 55 19, is spaced above the surface of the exten-

sion 16 so that it is obvious that the pull on cable 13 in use will cause that portion of the cable which crosses the upper or inner surface of extension 16 to tightly engage and grip the free end 17 of the loop. 60

It is thus obvious that the device is of strong integral construction, not only capable of effective efficient operation, but free from danger of failure of working parts through the result of rust or the result of 65 rough handling in the use to which devices of this nature are invariably put.

I claim:

1. A cable take up consisting of a ring-shaped body of oval form having a reduced 70 substantially flat extension projecting in the direction of its longitudinal axis beyond one end and also having a surrounding cable receiving groove, and a cable-guiding anchor at the end of said extension which is 75 spaced from the grooved portion of the body and provided with ends projecting laterally beyond opposite sides of the body extension, the lower surfaces of said ends being approximately in the plane of the upper edge 80 of the groove of the body, as described.

2. A cable take up consisting of a ring-shaped body having a peripheral cable receiving groove and an endwise projecting external body extension presenting an upper 85 cable receiving surface in the plane of one side edge of the groove, and an integral cable guide disposed transversely of said extension at the outer end of the latter, having oppositely extending ends projecting beyond 90 the sides of the extension with their lower surfaces in the plane of the other side edge of the body groove, as and for the purpose described.

3. A cable take up having a ring-shaped 95 body provided with an integral outwardly projecting extension presenting a substantially flat surface for the crossed extensions of a cable loop, said body having a peripheral groove for the reception of a cable loop 100 at one side of the said crossed extensions, and a transverse guide at the outer end of said extension having its ends projecting beyond opposite sides of the extension to receive therebeneath the extensions of the cable loop at the opposite side of said crossed extensions thereof. 105

In testimony whereof I have affixed my signature.

JOHN HENRY ROSEMEYER.
